UNITED STATES PATENT OFFICE.

JAMES A. WATSON, OF WASHINGTON, DISTRICT OF COLUMBIA, ASSIGNOR
OF ONE-HALF TO RALPH W. LEE, OF SAME PLACE.

DESIGN FOR A LAWN-SPRINKLER STAND.

SPECIFICATION forming part of Design No. 30,543, dated April 11, 1899.

Application filed March 6, 1899. Serial No. 708,038. Term of patent 7 years.

To all whom it may concern:

Be it known that I, JAMES A. WATSON, a citizen of the United States, residing at Washington, in the District of Columbia, have invented and produced a new and original Design for a Lawn-Sprinkler Stand, of which the following is a specification.

In the accompanying drawings, forming a part of this specification, Figure 1 is an end view of the lawn-sprinkler stand, and Fig. 2 is a perspective view of the same.

As shown in the drawings, the material features of my design consist of a flat annular platform *b*, a flaring flange or skirt *c*, depending from the outer portion of the part *b*, flat outwardly-flaring runners *d*, triangular in

general outline, having rounded lower corners *e*, circular openings *f*, and curved portions *g*, connecting said runners with the portion *c*.

Having described my invention, what I claim, and desire to secure by Letters Patent, is—

The design for the lawn-sprinkler stand, substantially as shown and described.

In testimony whereof I affix my signature in presence of two witnesses.

JAMES A. WATSON.
